UNITED STATES PATENT OFFICE.

ALONZO E. RHOADES, OF HOPEDALE, MASSACHUSETTS, ASSIGNOR TO DRAPER CORPORATION, OF HOPEDALE, MASSACHUSETTS, A CORPORATION OF MAINE.

QUICK-ACTING WARP STOP MECHANISM FOR WARPERS HAVING AN OSCILLATORY DETECTOR BAR.

Application filed February 11, 1926. Serial No. 87,644.

This invention relates to improvements in quick-acting warp stop mechanisms for warpers having detector mechanism of the type which comprises pivotally mounted 5 drop wires and a co-operating detector bar oscillating transversely of the plane of said drop wires, and the general object of the invention is to provide means for more quickly stopping the warper than in warp 10 stop mechanisms heretofore employed.

The present invention relates to a modified form of quick-acting warp stop mechanism, the principle of which is broadly disclosed in an application for patent which 15 is filed concurrently herewith, Serial No. 87,643.

The breakage of a warp coming from the creel to the warper may occur near the beam upon which it is to be wound or the warp 20 may break in front of the stop motion and the trailing end carried on to the beam. In usual constructions where the stoppage 25 of the warper is delayed after detection of a broken warp many yards of the warp are apt to be carried along before the warper is completely stopped so that in piecing the ends it is almost impossible not to cross them for if the ends are wound around the beam, or the broken end has to be found after it 30 has been wound upon the beam, it is almost impossible to piece up and keep the warps in line. Consequently, frequently the warps are crossed. By the present invention the warper is stopped in a small fraction of the 35 time required for the stoppage of the ordinary warper; consequently, there is much less run-over of the yarn. Furthermore, the prompt stoppage of the warper enables the broken end readily to be found before it has 40 been wound upon the beam, thus saving a crossing of the warps.

One of the objects of the invention is to provide a drop wire construction comprising a pivotally mounted drop wire which 45 is so constructed as to arrest the transversely oscillating movement of the detector bar in either direction of movement thereof.

Another object of the invention is to provide means for oscillating the drop wire bar from a continually moving vibrator including controlling means operable upon the 50 arrest of the detector bar by a falling drop wire to cause the knock-off device to effect a stoppage of the warper.

A further object of the invention is to 55 provide a continually moving actuator having means operable at a greater speed than the speed of movement of the vibrator to actuate the knock-off device when engaged thereby and controlling means for causing 60 said knock-off device to engage said actuator upon arrest of the detector bar in either direction of its movement, thereby effecting a prompt stoppage of the warper.

Other objects and features of the invention will more fully appear from the following description and the accompanying drawings and will be particularly pointed out in 65 the claims.

A preferred embodiment of the invention 70 is illustrated in the accompanying drawings as applied to the usual type of warper, only such portion of the warper frame being illustrated as is required to show the application of the invention.

In the drawings:

Fig. 1 is an elevation of one of the end 75 frames of the warper partially broken away to show the position of the drop wire mechanism or detector mechanism;

Fig. 2 is an enlarged detail rear elevation 80 of a portion of the end frame of the warper showing the mechanism for transmitting an oscillatory movement to the detector bar shaft and the means for controlling the knock-off device which, when actuated, effects a stoppage of the warper, the parts being shown in position to effect a stoppage 85 of the warper; and

Fig. 3 is an enlarged detail view illustrating 90 the action of the drop wire in arresting the oscillatory drop wire bar and its shaft and the relative rotative movement of the clutch members when the drop wire bar is arrested.

The warper may be of the usual type comprising end frames 1 and 2 which carry the usual mechanism of the warper and upon which is mounted the detector mechanism and the means operable thereby for effecting a stoppage of the warper. A bar 3, extending transversely between the end frames of the warper, is provided with a seat 4 which supports the usual series of blocks 5, in each of which a plurality of drop wires 6 is pivotally mounted and retained in separated position. A usual restoring bar 7 is carried upon an arm 8 which is secured

to a rock shaft 9. The bar 7 serves the double purpose of arresting the falling drop wires in substantially horizontal position in the path of the vibrating detector and when 5 moved upwardly by the rocking of the shaft 9 to return a released drop wire to position. The ends of usual drop wires are bent upwardly and then reversely bent to provide an eye for a warp. In the present 10 construction the ends of the drop wires are bent downwardly, that is to say, in the reverse direction. Preferably the free end of the drop wire is first bent abruptly downwardly to present an outer shoulder 15 10 and then carried in parallelism with the shank of the drop wire bar and reversely bent, preferably in substantially the plane of the shank, to provide an eye 11 and also to present an inner shoulder 12 adapted to 20 engage the detector bar.

The oscillating detector bar 13 is in the form of a flat plate extending transversely of the warper and desirably is provided at its upper end with laterally extending 25 flanges 14 and 15 to insure proper engagement with the falling drop wire. The detector bar 13 is carried upon arms 16 extending upwardly from and fixedly secured to a detector bar shaft 17 which is journalled 30 in the end frames of the warper and is so located with respect to the drop wires that a falling drop wire will arrest the detector bar substantially midway of the limits of its oscillatory movement. By virtue of the 35 downwardly bent end of the drop wire to form an eye for the warp, the falling drop wire will either present its outer end as an abutment to arrest the movement of the detector bar in one direction when the drop 40 wire falls into engagement with the restoring bar 7, as is illustrated in dotted lines in Fig. 3, or if the detector bar is moving in the opposite direction, the shoulder 12 will hook over the upper edge of the detector 45 bar and thereby arrest its movement, as is illustrated in Fig. 3. The flanges 14 and 15 at the upper edge of the detector bar will prevent the drop wires from being forced upwardly out of engagement with the detector bar, thereby insuring the prompt 50 stoppage of the movement of said bar.

By reason of the fact that the detector bar is thus arrested during either direction of its movement, the stop mechanism of the 55 warper may be more quickly operated than in previous constructions in which the drop wire arrests the detector bar in only one of its directions of movement.

A further object of the invention is to 60 provide additional means for still more quickly stopping the warper upon the arrest of the detector bar. In the present invention the oscillatory movement is imparted to the detector bar from the usual continually 65 acting vibrator 18 through suitable trans-

mitting and controlling mechanism which is operable upon the arrest of the oscillating detector bar to cause engagement between a knock-off device and a continually moving actuator having means to engage and 70 operate the knock-off device at a greater speed than the speed of movement of the vibrator. In the particular construction illustrated a collar 19 is fixedly and preferably adjustably secured to the detector bar 75 shaft by a set screw 20. The collar 19 is provided with a clutch face having a cam surface preferably in the form of a re-entrant angle presenting symmetrical faces 21 and 22. A complementary movable 80 clutch member 23 is rotatably and slidably mounted upon the detector bar shaft 17 and is provided with a cam-shaped face 24 complementary to the faces 21 and 22 of the collar. The clutch faces are normally 85 held in engagement by a helical spring 25 surrounding the shaft 17 and abutting at one end against the movable clutch member 23 and at its opposite end against a suitable abutment which may be a collar 26 fixedly 90 secured to the shaft and having an arm 27 connected to and operated by the clock mechanism of the warper (not shown).

The clutch member 23 is provided with a downwardly extending arm 28 to which is pivotally mounted the bifurcated upper end 29 of a link 30, the lower end of which is connected by a pin and slot connection 31 and 32 to the upper end of the vibrator 18. In the normal operation of the machine, therefore, the vibrator 18 oscillates the lower end of the link about the axis of the detector bar shaft 17 and acting through the clutch members imparts an oscillatory movement to the detector bar 13. Upon arrest 1 of the detector bar by a falling drop wire the detector shaft 17 is prevented from rotation and inasmuch as the clutch member 23 is necessarily oscillated by the movement of the vibrator and connecting link 30, the 1 movable clutch member 23 will be caused to slide along the shaft 17 against the resistance of the spring 25 by the camming action of the complementary cam faces of the clutch member and collar. This sliding 1 movement of the movable clutch member is employed to control the actuation of the knock-off mechanism to arrest the warper.

The preferred construction illustrated herein comprises a knock-off device 33 which is pivotally mounted upon a stud 34 upon the end of a horizontal lever 35 which is fulcrumed upon a suitable stud 36 extending from the end frame of the warper. The knock-off device has a laterally extending 1 arm 37 which is connected by a link 38 to the usual knock-off lever 39 which, when actuated, knocks off the shipper lever 40. The knock-off device 33 is provided with a 1 downwardly extending end presenting a

shoulder 41 adapted to be engaged by a continually moving actuator having means operable to actuate the knock-off device when engaged thereby at periods of greater frequency than the frequency of movement of the vibrator.

In the particular construction illustrated the actuator comprises a star wheel 42 which is carried by a continually rotating shaft 10 43 driven at such suitable speed that the teeth 44 of the actuator when engaged by the knock-off device will promptly actuate the latter to cause a stoppage of the warper. The knock-off device is normally held in elevated position by controller mechanism which is operable to permit or cause the knock-off device to engage the actuator promptly upon arrest of the vibrating detector bar. In the present embodiment of 20 the invention the lever 35, which supports the knock-off device 33, is provided midway of its length with an arm 45. The end of this arm is connected by an adjustable link 46 with a looped end 47 of an arm or rod 25 48 which is seated in the depending end 49 of one arm 50 of a controlling lever which is pivotally mounted upon a stud 51 projecting from a bracket 52 secured to the end frame and the other arm 53 of which 30 lever is provided with a rounded end portion 54, which engages the side 55 of an enlarged upper portion of the link 30 through which oscillatory movement is 35 transmitted from the vibrator to the detector bar shaft.

In the normal operation of the warper the spring 25 forces the movable clutch member 23 along the detector bar shaft 17 until its clutch face 24 engages the complementary 40 clutch faces 21 and 22 of the collar, thereby locking the clutch member and collar together so that the shaft 17 is oscillated through the link 30 in synchronism with the movement of the vibrator 18. When a detector bar is arrested by a falling drop wire in either direction of its movement, rotation of the detector bar shaft 17 is prevented so that a relative rotary movement, which is imparted to the movable clutch member 23, 45 causes the clutch member to ride up upon one of the cam faces 21 and 22 of the collar. This in turn moves the clutch member 23 longitudinally of the shaft against the pressure of the spring 25. As the clutch member 50 23 thus moves, the swinging upper end of the link 30, which is pivotally connected to the clutch member, moves away from the end frame and consequently permits the upwardly extending arm 53 of the controlling 55 lever to swing about the pivotal stud 51, thereby permitting the arm 48 and the knock-off device, which is connected to it, to drop so that the shoulder 41 of the knock-off device will lie in the path of the teeth 44 of the actuator. In view of the relatively

rapid movement of these teeth, the knock-off device will be promptly engaged and actuated to effect a stoppage of the warper.

It will be obvious from the above disclosure that a quick stoppage of the warper is produced by virtue of the fact that the detector bar will be arrested at substantially the limit of its oscillation during either direction of its movement and that the controlling mechanism will be promptly operated by the arrested detector bar to cause engagement between the knock-off device and the rapidly moving actuator.

It will be understood that the embodiment of the invention disclosed herein is of an illustrative character and is not restrictive and that various changes in form, construction and arrangement of parts may be made within the spirit and scope of the following claims.

Having thus described the invention, what is claimed as new, and desired to be secured by Letters Patent, is:

1. Quick-acting warp stop mechanism for warpers comprising a transverse, oscillating, detector bar, a series of pivotally mounted drop wires each having its free end normally supported by a warp and provided at said free end with means operable upon the falling of the drop wire to engage and arrest the detector bar during either direction of its movement and means operable by the arrest of said detector bar to stop the warper.

2. Quick-acting warp stop mechanism for warpers comprising an oscillating detector bar, a series of drop wires each pivotally mounted at its lower end and having its upper end provided with an eye for a warp and presenting an outer and an inner shoulder operable upon the falling of the drop wire respectively to abut against or to hook over the detector bar and thereby arrest it during its movement in either direction and means operable by the arrest of said detector bar to stop the warper.

3. Quick-acting warp stop mechanism for warpers comprising an oscillating detector bar, a series of drop wires each pivotally mounted at its lower end and bent downwardly and reversely at its upper end to provide an eye for a warp with a threading slot leading thereto and to present outer and inner shoulders operable upon the falling of the drop wire respectively to abut against or to hook over the detector bar and thereby arrest it during either direction of its movement and means operable by the arrest of said detector bar to stop the warper.

4. Quick-acting warp stop mechanism for warpers comprising an oscillating detector bar having flanges extending laterally from the upper edge thereof, a series of drop wires each pivotally mounted at its lower end and having at its upper end an eye for a warp

and presenting an outer and an inner shoulder operable upon the falling of the drop wire respectively to abut against the bar below one flange or to hook over the other flange thereof, means to limit the falling movement of said drop wires to cause the shouldered outer end thereof to co-operate with said detector bar and means operable by the arrest of said detector bar to stop the 10 warper.

5. Quick-acting warp stop mechanism for warpers comprising an oscillating detector bar, a series of drop wires each pivotally mounted at its lower end and having its upper end provided with an eye for a warp and presenting an outer and an inner shoulder operable upon the falling of the drop wire respectively to abut or hook over a detector bar and thereby arrest it during its 15 movement in either direction, a continually moving vibrator, a knock-off device, controlling mechanism releasably connected to said detector bar and operable by said vibrator to oscillate said detector bar and means 20 operable by said controlling mechanism when released by the arrest of a detector bar to actuate said knock-off device and thereby effect the stoppage of the warper.

6. Quick-acting warp stop mechanism for 30 warpers comprising an oscillating detector bar, a series of drop wires each pivotally mounted at its lower end and having its upper end provided with an eye for a warp and presenting an outer and an inner shoulder operable upon the falling of the drop wire respectively to abut or hook over a detector bar and thereby arrest it during its movement in either direction, a continually moving vibrator, a knock-off device, an actuator 35 having means operable at a greater speed than the speed of movement of said vibrator to actuate said knock-off device when engaged thereby, controlling mechanism releasably connected to said detector 40 bar and operable by said vibrator to oscillate said detector bar and means operable by said controller upon arrest of said detector bar to cause said knock-off device to engage said actuator and thereby effect a prompt 45 stoppage of the warper.

7. Quick-acting warp stop mechanism for 50 warpers comprising an oscillating detector bar shaft having a detector bar fixedly secured thereto, a series of pivotally mounted drop wires each having at its free end means to engage and arrest said detector bar in either direction of its movement, a clutch member fixedly secured to said detector bar shaft and a loose clutch member rotatably 55 and slidably mounted upon said shaft, said clutch members presenting symmetrical, interengaging cam faces, a knock-off device, a continually moving vibrator, means for oscillating said shaft from said vibrator 60 and through said clutch members and means

operable by the sliding movement of the loose clutch member upon said shaft, caused by the action of said cam faces upon arrest of a detector bar, to actuate said knock-off device and thereby effect a stoppage of the 70 warper.

8. Quick-acting warp stop mechanism for warpers comprising an oscillating detector bar shaft having a detector bar rigidly secured thereto, a series of drop wires each 75 operable when permitted to fall to arrest said detector bar, a collar fixedly secured to said detector bar having a clutch face presenting a cam, a clutch member rotatably and slidably mounted upon said detector bar shaft having a clutch face complementary to the face of said collar, a continually moving vibrator, a link pivotally connected at one end to said vibrator and at its other end to said movable clutch member, yieldable means acting upon said movable clutch member normally holding the said clutch face in engagement with said collar, whereby oscillatory movement will be imparted to said detector bar shaft from said vibrator, but upon arrest of the detector bar the camming action of said clutch faces will cause the movable clutch member to slide longitudinally of said shaft and a knock-off device operable by the sliding movement of 85 said movable clutch member to effect a stoppage of the warper.

9. Quick-acting warp stop mechanism for warpers comprising an oscillating detector bar shaft having a detector bar rigidly secured thereto, a series of drop wires each 90 operable when permitted to fall to arrest said detector bar, a collar fixedly secured to said detector bar having a clutch face presenting a cam, a clutch member rotatably and slidably mounted upon said detector bar shaft having a clutch face complementary to the face of said collar, a continually moving vibrator, a link pivotally connected at one 95 end to said vibrator and at its other end to said movable clutch member, yieldable means acting upon said movable clutch member normally holding the said clutch faces in engagement with said collar, whereby oscillatory movement will be imparted to said detector bar shaft from said vibrator, but upon arrest of the detector bar the camming action of said clutch faces will cause the movable clutch member to slide longitudinally of said shaft, a knock-off device, an actuator having means operable at a greater speed than the speed of movement of said vibrator to actuate said knock-off device when engaged thereby, controlling mechanism releasably connected to said detector 100 bar and operable by said vibrator to oscillate said detector bar and means operable by said controller upon arrest of said detector bar to cause said knock-off device to engage said actuator and thereby effect a prompt 105 stoppage of the warper.

10. Quick-acting warp stop mechanism 110 for warpers comprising an oscillating detector bar shaft having a detector bar rigidly secured thereto, a series of drop wires each operable when permitted to fall to arrest said detector bar, a collar fixedly secured to said detector bar having a clutch face presenting a cam, a clutch member rotatably and slidably mounted upon said detector bar shaft having a clutch face complementary to the face of said collar, a continually moving vibrator, a link pivotally connected at one end to said vibrator and at its other end to said movable clutch member, yieldable means acting upon said movable clutch member normally holding the said clutch faces in engagement with said collar, whereby oscillatory movement will be imparted to said detector bar shaft from said vibrator, but upon arrest of the detector bar the camming action of said clutch faces will cause the movable clutch member to slide longitudinally of said shaft, a knock-off device, a continually moving actuator having means operable at a greater speed than the speed of movement of said vibrator to actuate said knock-off device when engaged thereby and means operable by the sliding movement of said clutch member upon said detector bar shaft to cause said knock-off device to engage said actuator and thereby effect a stoppage of the warper.

11. Quick-acting warp stop mechanism 115

for warpers comprising an oscillating detector bar shaft having a detector bar rigidly secured thereto, a series of drop wires each operable when permitted to fall to arrest
5 said detector bar, a collar fixedly secured to said detector bar having a clutch face presenting a cam, a clutch member rotatably and slidably mounted upon said detector bar shaft having a clutch face complementary to
10 the face of said collar, a continually moving vibrator, a link pivotally connected at one end to said vibrator and at its other end to said movable clutch member, yieldable means acting upon said movable clutch member
15 normally holding the said clutch faces in engagement with said collar, whereby oscillatory movement will be imparted to said detector bar shaft from said vibrator, but upon arrest of the detector bar the camming
20 action of said clutch faces will cause the movable clutch member to slide longitudinally of said shaft, a knock-off device, a continually rotating star wheel having arms operable at a greater speed than the speed of
25 movement of said vibrator to actuate said knock-off when engaged thereby, a controlling lever having one arm connected to said knock-off lever and another arm engaging the link connecting said vibrator to said
30 movable clutch member operable by the lateral movement of said link caused by the sliding movement of the movable clutch member to permit said knock-off device to engage the teeth of said star wheel and thereby effect a stoppage of the warper.
35

11. Quick-acting warp stop mechanism for

warpers comprising an oscillating detector bar shaft, a collar fixedly secured to said shaft having a re-entrant clutch face presenting symmetrically inclined walls, a detector bar rigidly secured to said shaft, a series of drop wires each operable when permitted to fall to arrest the detector bar in either direction of its movement, a continually moving vibrator, a link pivotally connected at its lower end to said vibrator, a movable clutch member slidably mounted on said detector bar shaft and having a face complementary to the re-entrant clutch face of said collar, yieldable means engaging
40 said movable clutch member acting normally to hold the complementary clutch faces of said clutch member and collar in engagement, but yieldable in response to the camming action of said clutch faces caused by
45 relative rotary movement of said movable clutch member and collar upon arrest of said detector bar to permit the movable clutch member to slide longitudinally of the shaft, a knock-off device, a rotary star wheel, the
50 arms of which move more rapidly than the speed of movement of said vibrator operable to actuate said knock-off when engaged thereby and means operable by the longitudinally sliding movement of said movable
55 clutch member to cause said knock-off device to engage said actuator and thereby cause prompt stoppage of the warper.

In testimony whereof, I have signed my name to this specification.

ALONZO E. RHOADES.
